T. J. BOWDLE, S. R. LAWDER, AND F. E. JOHNSTON, OF PIQUA, OHIO.

Letters Patent No. 82,792, dated October 6, 1868.

IMPROVEMENT IN MACHINES FOR TENONING BLIND-SLATs.

The Schedule referred to in these Letters Patent and making part of the same.

TO ALL WHOM IT MAY CONCERN:

Be it known that we, T. J. BOWDLE, S. R. LAWDER, and F. E. JOHNSTON, of Piqua, in the county of Miami, and State of Ohio, have invented a new and improved Machine for Tenoning Blind-Slat; and we do hereby declare the following to be a full and exact description thereof, reference being had to the accompanying drawings, forming a part of this specification, in which—

Figure 1 is a plan view of our blind-slat tenoner, with movements thereof illustrated in red lines.

Figure 2, a plan view of the same reversed, showing the under side thereof, having also an illustration of its movement in red lines.

Figure 3; a section in the line $x-x$, and

Figure 4 a section in line $y-y$ of fig. 1.

Similar letters indicate like parts in each of the figures.

The nature of our invention consists in the combination of a T-shaped centrally-pivoted lever, with suitable toggle-joint levers, for the purpose of moving a pair of sliding bits or cutters to and from each other, so as to cut and form the shoulders upon the end of a blind-slat.

Also, in causing, by means of a suitable link connecting the T-shaped vibrating lever with a collar actuating a sliding tubular centre-bit, an approach of said tubular bit simultaneously with the approach of the shoulder-bits, to cut and form a journal upon the end of the slat.

Also, in imparting a rotary movement to said tubular bit, in its approach to the slat, by means of a pin in the box or collar supporting the bit engaging a spiral groove on the periphery thereof, or *vice versa*.

To enable others skilled in the art to make and use this our invention, we will proceed to describe its construction and operation.

Upon a suitable table or bed-plate, A, we secure, in a right line, ways B B' B B', figs. 1 and 2, between which the carriages or stocks C C, which carry the shoulder-bits or cutters A A, slide freely.

An interval is left between the opposite ends of the ways, sufficient to allow the introduction of the slat to be tenoned, and of the devices for securing the same, as seen in fig. 1.

To each carriage, C, is secured an arm, D, (see fig. 3,) projecting downward through a slot cut in the table between the ways B and B', of such a length as to permit the extent of movement required in the bit-carriages C. These arms D, instead of being fastened immovably to the carriages C, pass through slots, b, therein, and are secured at any desired point along the slots by means of set-screws c, so as to permit an adjustment of the carriages with reference to the levers connected to said arms D, as hereinafter described.

At right angles to the ways B B' B B', and in a line central between the opposite ends thereof, we support, in suitable boxes, E E, a tubular bit, F, so that it may not only slide freely back and forth, but also revolve therein.

A loose collar, G, having an arm, H, fig. 2, projecting downward through a slot, d, cut in the table in the line of movement of the bit, encircles the same midway between its bearings at E E, and is held in place by adjusting-rings I, fig. 1, secured to the bit, on either side of the collar, by means of set-screws i i.

In a right line with said tubular bit, and on the opposite side of the bit-carriages C C, is placed a supporting-block, K, to hold the end of the slat to be tenoned, (see slat in red lines, fig. 1,) secured by a clamp, f, sliding in a slot, g, fig. 1, in the table beneath, which permits its adjustment at a proper distance from the bits. This block is fitted with guide-pieces and set-screws to hold and secure the end of the slat in a proper position whilst the bits a are cutting the same.

Provision is also made for the support of the other end of the slat, by means of a second block, K', secured also by a clamp sliding in the same slot g, which is extended for the purpose to the outer edge of the table, and provided with suitable retaining-devices and set-screws.

A carriage, L, is arranged to slide vertically in ways h h, fig. 2, against the end of the table at the termination of the slot g, in which is formed a groove, g', to receive the clamp of the rear block K', so that the block

may slide along the slot g into the groove g' of the carriage L , and be elevated vertically whenever the character of the work requires that the slat be inclined whilst being tenoned.

A bent T-shaped lever, P , fig. 2, is pivoted centrally to the under side of the table, so that its pivot, h , shall be at the intersection of the axis of the tubular bit with the line of movement of the shoulder-bits. The long arm K of the lever P extends out beyond the side of the table, and forms a handle wherewith to vibrate the same.

To the end of each of the shorter arms, $p' p''$, of the lever is pivoted a short link, $M M'$, extending to a toggle-joint formed by two short levers $N N$, the one pivoted to the table, and the other to a plate on the rod or arm D , extending through the slot from the shoulder-bit carriage above, the shorter arms, $p' p''$, of the lever extending in opposite directions, being so bent as to project respectively on opposite sides of the line of the slots beneath the bit-carriages $C C$, (see dotted lines, fig. 1.) Hence, by vibrating the long arm p , of the lever P , the shorter arms $p' p''$, rocking or swinging upon the pivot h of the lever, will double the toggle-joints $N N$, and thus cause the carriages $C C$ to slide in their ways.

The adjustment of the toggle-levers N with the actuating-lever P and with the sliding carriages C , is so made as that the bits a shall be closed upon the slat when the toggle-levers are straight, so that a vibration of the lever P in either direction will, by bending the joints, cause the bits to separate.

The movements of the lever P may be so controlled as to allow it to pass beyond the dead-point of the toggles, (as illustrated by red lines, fig. 2,) so as to cause, by the continued movement of the lever in one direction, a slight withdrawal of the shoulder-bits after they have closed, and, upon its reversal, to cause them to close again before they are finally separated after cutting the shoulders upon the slat.

To obtain an approach of the tubular centre-bit F simultaneously with the closing of the shoulder-bits $a a$, we connect the arm H , projecting from the collar G thereon, with one arm, p' , of the lever P ; by means of a pivoted link, R , so adjusting the link as that the tubular bit F shall advance towards the end of the slat at the same time that the side bits a are closing to cut the shoulders thereon. Where a movement of the lever P , to push the toggle-levers N beyond their right line or dead-point, as illustrated in red lines, fig. 2, is allowed, so as to cause the bits a to withdraw again slightly after closing the tubular bit will still continue to advance steadily until the lever P is reversed.

This combination and adjustment of the lever P with the toggle-levers N is desirable, inasmuch as the side bits a , closing once more upon the shoulders previously cut on the slat before they are entirely withdrawn therefrom, will give a finish thereto, removing all roughness or imperfection therefrom.

A pin, s , fig. 4, in the inner periphery of the front box or collar E' of the tubular bit, engages in a spiral groove, t , cut on the outer surface of said bit, so that as the bit moves forward it is made to revolve slowly in its bearings within the boxes $E E'$.

The rings I , held by set-screws $i i$ on either side of the loose collar G , permit an adjustment of the bit to or from the shoulder-bits a . These are held in their stocks or carriages C by suitable set-screws v .

The carriages C are themselves adjustable by means of the arms D in the slots b of the carriages.

Having thus fully described our invention, we claim therein as new, and desire to secure by Letters Patent—

1. A T-shaped vibrating lever P , in combination with toggle-joint levers $N N$, suitable connecting-links $M M'$, and with sliding carriages $C C$, carrying the shoulder-cutting bits $a a$ of a slat-tenoning machine, all arranged and operating substantially as and for the purpose herein set forth.

2. In combination with the foregoing devices, combining with one arm, p' , of said vibrating lever P , a connecting-link R , pivoted to a collar, G , embracing the tubular centre-bit F of the machine for the purpose of operating the same, all substantially as is herein specified.
